CIGARETTE PACKAGE

Edward W. Scharre, Louisville, Ky., assignor to Anaconda Aluminum Company, a corporation of Montana
Filed Feb. 17, 1966, Ser. No. 528,241
10 Claims. (Cl. 206—41.2)

This invention relates to a cigarette package and more particularly it relates to a cigarette package comprised of a sheet of coated foil and paper laminate which is constructed to prevent moisture escape from the package but is permeable to gas under pressure within the package.

Cigarette packages presently in use consist of an inner wrap, often a foil and paper laminate, and an outer cellophane wrap which is used to seal the package to preserve the freshness of the cigarettes. Notwithstanding the double wrapping construction of these cigarette packages, they still have a relatively short shelf life and efforts have long been made to develop a cigarette package having a single overwrap adaptable to modern wrapping machinery which will give greater shelf life.

It is an object of the package of the invention to provide a cigarette package which can consist of a single overwrap of coated foil and paper laminate folded and sealed with a structural arrangement that prevents moisture escape through seams and the body of the package but permits passage of gas under pressure within the package. A package which loses moisture too rapidly accelerates the spoilage of the tobacco but one that is too well sealed will retain the gas emitted during continued aging of the tobacco causing the tobacco to foul. The package of the invention balances these requirements in a novel construction which gives four to ten times the shelf life of the present cigarette packages.

Broadly stated, the cigarette package comprises a plurality of cigarettes grouped side by side with a unitary sheet of foil and paper laminated, coated on its foil side with a heat sensitive coating, convolutely wound about the cigarettes to form a tubular member with the paper lining the inside of the tubular member and end portions of the tubular member folded about the ends of the cigarettes to form a closed wrapper. A longitudinal seam is defined by one margin side edge portion of the sheet overlapping and heat sealed to the opposite marginal side edge portion and characterized by the overlapping marginal side edge portion being folded back against itself with the foil on the outside of the fold so that the longitudinal seam is defined by adhesively joined foil-to-foil faces of the marginal side edge portions. The folded end portions of the tubular member are folded with each overlapping portion having foil on the outside of the fold to define adhesively joined foil-to-foil faces and characterized by the marginal end edge of the outermost folded portion being folded back against itself with foil on the outside of the fold; moisture penetration through the package is prevented by the coating and the longitudinal seam and closed end construction, but gas under pressure in the package can permeate through the package.

Although this package can be used alone as the complete cigarette container, it will usually be covered by a decorative overwrap on which the brand name will be printed; this overwrap can be a rigid cardboard or plastic box of the type presently popular.

In addition to the novelty of the construction of the package itself, limited sizes of the aluminum foil and paper laminate and the coating have been determined which cooperate with the novel construction and have been found to give added shelf life to the cigarettes without substantial modification to existing cigarette packaging equipment.

A preferred embodiment is described hereinbelow with reference to the drawings wherein:

2

FIG. 1 is a plan view of a sheet of foil and paper laminated showing as dotted the intended fold lines;

FIG. 2 is a fragmentary perspective of the package showing one end portion partially closed;

FIG. 3 is a section taken along lines 3—3 of FIG. 1;

FIG. 4 is a perspective of the closed package showing the assembly of an overwrapper;

FIG. 5 is a fragmentary section taken along lines 5—5 of FIG. 4;

FIG. 6 is a fragmentary section taken along lines 6—6 of FIG. 4; and

FIG. 7 is a perspective of the package inserted in a rigid outer box.

As shown in FIG. 1 the unitary sheet of aluminum foil and paper laminate 10 has been cut to length usually after stripping from a feed roll. As shown in FIG. 3 the laminate consists of a paper ply 11 in a range of 20 pounds per ream to 30 pounds per ream bond paper of a thickness of approximately .0025 inch to .0037 inch thickness.

15 The foil ply 12 laminated to the paper ply 11 has a range of 10 pounds per ream to 14 pounds per ream and a thickness of approximately .00025 inch to .00035 inch. The foil is laminated to the paper in the usual way, usually with a casein latex base adhesive. The foil ply 12 is coated on its exterior surface with a heat sealable coating 13 which falls within a range of 1 pound per ream to 3 pounds per ream and a thickness of approximately .001 inch to .0003 inch. Of the heat sealable coatings which are available, those generally available to the art are a vinyl chloride-vinyl acetate copolymer plus wax (paraffin, carnauba etc.); for ease of application the vinyl resinous composition may be mixed with an acetone-toluene methyl ethyl ketone mixed solvent. The following two specific compositions have been used in the range listed 20 below with particular success:

35 (1) A vinyl acetate-vinyl chloride dibasic acid resin containing a certain amount of refined microcrystalline wax and a chemical plasticizer dissolved in suitable solvents

40 4% by weight, vinyl chloride-acetate resin
18% (86% vinyl chloride, 13% vinyl acetate copolymer with 1% maleic anhydride)

1% petroleum based wax-microcrystalline type

45 3% di-2-ethylhexyl phthalate

37% toluene

37% methyl ethyl ketone

50 (2) A vinyl acetate-vinyl chloride-dibasic acid resin with a microcrystalline wax dissolved in suitable solvents

24% by weight (86% vinyl chloride, 13% vinyl acetate copolymer with 1% maleic acid anhydride)

1% petroleum based wax-microcrystalline type

55 10% toluene

10% methyl ethyl ketone

55% acetone

The range of thickness of aluminum foil and paper 60 laminate coated with the heat sealable coating were determined empirically to satisfy the numerous criteria which must be satisfied to make a satisfactory package. As discussed generally above, if tobacco stands too long in a pouch too well sealed, the pressure in the pouch will

65 increase because of the gas liberated by the tobacco during continued aging. Under these conditions there is generated an off odor or winey smell from the tobacco. With the construction of the package of the invention tested in the ranges of laminate and coating given above

70 there was no pressurizing of the packs and no noticeable off odor after prolonged standing in the packages. Taste testing revealed a far superior taste to comparably aged

cellophane sealed cigarettes. The required moisture content of from 12 to 16.5 percent was maintained up to 700 hours as opposed to about only 125 hours for standard cellophane sealed packages when placed in 150° F. over calcium chloride.

Although the chemical composition of the coating can be varied and it is impossible to test all available and theoretical compositions which can be used, it is intended that any coating composition of the general type described which permits gas passage but retains moisture as specified can be used.

With respect to the laminate, no substantial variation of the range given can be used because it could not be adapted to present packaging equipment; moreover, thinner constructions would lack the necessary strength and durability of handling while heavier constructions would cause problems in top and bottom folding and would reduce speed in packaging due to slower heat transfer in the sealing areas.

In FIG. 1, the unitary sheet of aluminum and paper laminate 10 which has been cut to size is shown with its paper ply facing upward. The dotted lines in the figure indicate the points at which the laminate 10 will be folded but are not pre-scored folded lines. The sheet 10 is generally rectangular in shape and defines marginal side edges 14 and 15 and end edges 16 and 17. The length between the marginal side edge portions 14 and 15 is greater than the circumference of twenty cigarettes lined side by side in two rows to permit the sheet to be convolutely wound about the cigarettes to form a generally rectangular tubular shaped member substantially as shown in FIG. 2 with the paper lining the inside of the tubular member and end portions 18 and 19 folded about the end of the cigarettes to form a closed wrapper. A longitudinal seam 20 is defined by one marginal side edge portion 21 of the sheet overlapping and heat sealed to the opposite marginal side edge portion 22. The seam is characterized by the overlapping marginal side edge portion 21 being folded back against itself with the foil ply 13 on the outside of the fold so that the longitudinal seam is defined about adhesively joined foil-to-foil faces as best shown in FIG. 6.

Each end portion 18 and 19 of the package is formed with an identical folding scheme and therefore description of one end portion is sufficient for an understanding of the construction of the opposite end portion. A first end portion 23 along one elongated side of the rectangular tubular member defining either the front or back of the package is folded down against the ends of the cigarettes. Tuck portions 24 and 25 on opposite narrow sides of the rectangular package are folded down against the first end portion 23 in foil-to-foil adhesive contact along the overlapping marginal edges 26 and 27 defined by foil on the outside of the fold. A second end portion 28 along the elongated side opposite to the first end portion is folded down against the folded first portion 23 and tuck portions 24 and 25 in foil-to-foil adhesive contact. The outermost marginal portion 29 of the second end portion is folded back against itself with foil on the outside of the fold to define a marginal foil edge portion 30 in adhesive foil-to-foil contact with the first end portion as shown in FIG. 4. It is to be noted that the package is characterized throughout its construction in that all exposed edge portions are the outside of folds and are defined by foil, because the marginal edge is folded back against itself wherever its edge would be exposed on the exterior of the package. This positions the paper laminate within the body of the package and precludes wicking of moisture through the relatively porous paper ply to the exterior of the package as would be the case with simple overlap seams commonly used. It is by virtue of this construction that the moisture retention of the package is so greatly improved. All seams are heat sealed.

In most cigarette package constructions it is desirable to provide some means for ease of gaining access to the

cigarettes. This can be done by the insertion of tapes, by perforating score lines in the wrapper or any other modifications which have been devised over the years. Any of these easy opening means which are consistent with the properties of this package can be incorporated into the construction. One example is shown in the drawings. It consists of a strip 31 which can be a string or braided material which has been impregnated with wax. By impregnating this strip 31 with wax, the end portion 32 which extends laterally out from the seam 20 adjacent the top of the package will not provide a means of moisture escape from within the package. As shown in FIG. 1 the strip preferably extends from the seam 20 about one third of the circumference of the sheet thereby permitting one end edge portion of the package to be ripped open by simply grasping the end of the strip 32 and tearing the end portion of the package open.

As shown in FIG. 4, if desired the package of the invention can be inserted into an overwrap 34 and a revenue stamp or other sealing member 35 can be sealed to opposite sides of the overwrap 34 and overlap the top end of the package to hold the overwrap in place. Because of the construction of the package of the invention, the overwrap is really unnecessary and would be desirable only to provide an attractive overwrap on which the brand name of cigarettes could be attractively presented.

It is also contemplated to place the package in a rigid cardboard box 36 as shown in FIG. 7. Rigid boxes have gained acceptance and the cigarette package of the invention could easily be adapted to this type rigid outer container. Of course, it could also easily be placed in the rigid plastic boxes presently on the market.

By the construction of the package of the invention, moisture penetration is substantially prevented through the seams throughout the structure of the package; therefore the package has been found to retain moisture for four to ten times longer than the present cigarette package on the market. In addition, by the foil and paper laminate sheet composition which satisfy the requirement that it is permeable to gas released by the tobacco on aging there is no fouling of the cigarettes during prolonged shelf life as would be the case if the package were truly hermetically sealed.

I claim:

- 45 1. A cigarette package comprising a plurality of cigarettes grouped side by side and a unitary sheet of foil and paper laminate, coated on its foil side with a heat sensitive coating, convolutely wound about the cigarettes to form a tubular member with the paper lining the inside of the tubular member, and end portions of the tubular member folded about the ends of the cigarettes to form a closed wrapper, a longitudinal seam defined by one marginal side edge portion of the sheet overlapping and heat sealed to the opposite marginal side edge portion and characterized by the overlapping marginal side edge portion being folded back against itself with the foil on the outside of the fold so that the longitudinal seam is defined by adhesively formed foil-to-foil faces of the marginal side edge portions, said folded end portions of the tubular member folded with each overlapping portion having foil on the outside of the fold to define adhesively joined foil-to-foil faces and characterized by the marginal end edge of the outermost folded portion on each end being folded back against itself with foil on the outside of the fold, moisture penetration through the package being prevented by the coating and the longitudinal seam and closed end construction but gas under pressure in the package being permeable through the coated laminate.
- 50 2. A cigarette package of generally rectangular tubular shape according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the
- 55 3. A cigarette package according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the
- 60 4. A cigarette package according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the
- 65 5. A cigarette package according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the

- 70 6. A cigarette package according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the
- 75 7. A cigarette package according to claim 1, said end portions comprising a first end portion of the tubular member folded down against the ends of the cigarettes, tuck portions on opposite sides folded down against the first end portion in foil-to-foil adhesive contact with the first end portion along its marginal edges defined by foil on the outside of the

fold, and second end portions along the side opposite to the first end portion folded against the first and tuck portions in foil-to-foil adhesive contact with the outermost overlapping edge of the second end portion folded back against itself with foil on the outside of the fold to define a marginal foil edge portion in adhesive foil-to-foil contact with the first end portion.

3. A cigarette package according to claim 1 wherein said coated foil and paper laminate is aluminum foil from about 10 to 14 lbs. per ream laminated to bond paper of about 20 to 30 lbs. per ream.

4. A cigarette package according to claim 3 wherein said coating is a vinyl chloride-acetate resinous composition of about 1 to 3 lbs. per ream.

5. A cigarette package according to claim 1 wherein means are provided within the package for ease of opening by hand.

6. A cigarette package according to claim 5 wherein a wax impregnated strip extends through the longitudinal seam and at least partially around the inside of the package adjacent one closed end portion for ripping open the package.

7. A cigarette package according to claim 1 wherein an outer wrapper surrounds the package.

8. A cigarette package according to claim 7 wherein the outer wrapper is a rigid closed box.

9. A cigarette package according to claim 1, wherein the moisture content within the package can be maintained within the range of 12 to 16.5 percent for greater than 125 hours and up to about 700 hours when placed in 150° F. over calcium chloride.

10. A cigarette package according to claim 4 wherein the moisture content within the package can be maintained within the range of 12 to 16.5 percent for greater than 125 hours and up to about 700 hours when placed in 150° F. over calcium chloride.
